(57) **CLAIM**

The ornamental design for a display panel with animated graphical user interface, as shown and described.

DESCRIPTION

1. Display panel with animated graphical user interface
2. Display panel with animated graphical user interface
1.1 is a front view of a first image of a display panel with animated graphical user interface;
1.2 is a second image thereof;
1.3 is a third image thereof;
1.4 is a fourth image thereof;
1.5 is a fifth image thereof;
1.6 is a sixth image thereof;
1.7 is a seventh image thereof;
1.8 is an eighth image thereof;

2.1 is a front view of a first image of a display panel with animated graphical user interface showing a second embodiment thereof;
2.2 is a second image thereof;
2.3 is a third image thereof;
2.4 is a fourth image thereof;
2.5 is a fifth image thereof;
2.6 is a sixth image thereof;
2.7 is a seventh image thereof; and
2.8 is an eighth image thereof.

The appearance of the animated graphical user interface transitions sequentially between reproductions 1.1-1.8 in embodiment 1, and 2.1-2.8 in embodiment 2. The process or period in which one image transitions to another forms no part of the claimed design.

The broken lines showing a display panel illustrates portions of the article and form no part of the claimed design.
